UNITED STATES PATENT OFFICE.

CLIFFORD DE B. KENNARD, OF WINNIPEG, MANITOBA, CANADA.

SWIMMING-GLOVE.

1,185,411.

Specification of Letters Patent. Patented May 30, 1916.

Application filed June 9, 1914. Serial No. 844,023.

To all whom it may concern:

Be it known that I, CLIFFORD DE BOCK KENNARD, subject of the King of Great Britain, residing at Winnipeg, in the 5 Province of Manitoba and Dominion of Canada, have invented certain new and useful Improvements in Swimming-Gloves, of which the following is a specification.

This invention relates to swimming gloves, 10 and one of the principal objects of the invention is to provide a glove made of thin rubber or elastic seamless material which will fit the hand and said glove being provided between the fingers and between the 15 index finger and thumb with webs made of elastic material which will stretch to form a comparatively flat surface to be presented to the water and which will give and collapse when the fingers are closed.

20 Another object of the invention is to provide a glove for use by swimmers which will increase the speed of the swimmer and which will be provided with elastic webs between the fingers and between the front 25 finger and thumb, said glove being made of a comparatively thin rubber film and provided with perforations upon the back of the glove, while the front of the glove is imperforate, the perforations in the back of 30 the glove serving to express the water from the inner side of the glove.

These and other objects may be obtained by means of the construction illustrated in the accompanying drawing, in which, 35 Figure 1 is a view looking at the back of the glove with the web extended, and Fig. 2 is a sectional view taken on the line 2—2 of Fig. 1.

Referring to the drawing, the numeral 1 40 designates the back portion of the glove, and 2 are perforations formed at intervals throughout the back portion and upon the fingers and thumb of the glove to serve in permitting the water to escape which may 45 gather about the wrist or within the glove.

Connected centrally between the little finger and the next finger is a web 3 made of elastic rubber of a thickness somewhat greater than the thickness of the material 50 from which the glove is made. The web 3 is secured to the inner sides of the fingers

4 and 5 at a point central to the front and back of the finger. A webbing 6 is secured between the finger 5 and the finger 7 in the same manner centrally between the front 55 and back of said finger. A web 8 is also secured between the index finger 9 and the finger 7, and a web 10 of considerable area is secured between the index finger 9 and the thumb 11. The wrist portion 12 of the 60 glove is imperforate and is sufficiently contracted to closely fit upon the wrist of the wearer.

In use, the fingers of the user of the glove are slightly curved, so as to have the full 65 contact with the water. The webbing between the fingers and thumb are fully extended to give a large area of impact surface during the stroke of the swimmer and during the return stroke the fingers are 70 closed so that but little surface will be presented to the water, thus serving to feather the strokes.

From the foregoing it will be obvious that a swimming glove made in accordance with 75 this invention will serve to give considerable speed to the user, and the glove will be found very useful for beginners in learning to swim. The back portion of the glove being provided with perforations will express or permit the water to pass out upon 80 the contraction of the hands of the swimmer on the return stroke, and the webs between the fingers and between the front finger and thumb can be extended to give a large 85 contacting surface to the water. The gloves are made and used in pairs, and may be used to advantage in playing water polo, permitting the player to tread water with the hands instead of the feet, and preventing 90 players from getting scratched with the finger nails.

Various changes may be made in the details of construction without departing from the spirit and scope of the invention as defined in the claim. 95

What is claimed is:

A swimming glove formed of sheet rubber having a palm and back portion, a tight fitting wristlet formed upon said glove, the 100 palm of said glove and fingers being imperforated and the back portion of said

glove having perforations extending from the finger tips to said wristlets, whereby upon the contraction of the hand in the water, water is expressed from the inner side of the glove, webs secured between the fingers and being of such width as to allow the fingers to be stretched at normal distance holding said webbing taut for assisting

the swimmer in making a strong stroke substantially as described.

In testimony whereof I affix my signature in presence of two witnesses.

CLIFFORD DE B. KENNARD.
